UNITED STATES PATENT OFFICE.

JAMES W. MANSFIELD, OF BOSTON, MASSACHUSETTS, ASSIGNOR TO THE STANDARD MACHINERY COMPANY, OF MYSTIC, CONNECTICUT.

SHEET-FEEDING MACHINE.

SPECIFICATION forming part of Letters Patent No. 635,792, dated October 31, 1899.

Application filed February 15, 1898. Serial No. 670,441. (No model.)

To all whom it may concern:

Be it known that I, JAMES W. MANSFIELD, of Boston, county of Suffolk, and State of Massachusetts, have invented certain new and 5 useful Improvements in Sheet-Feeding Machines; and I do hereby declare the following specification, taken in connection with the accompanying drawings, forming a part of the same, to be a full, clear, and exact description 10 thereof.

The invention relates to that class of machines in which a body of combed-out or feathered sheets is placed upon an upper supply-table and is slowly fed from the same to 15 a lower feed-table, where the individual sheets are separated from the body of sheets and advanced to registering devices by which each sheet is brought into the correct position to be taken by the grippers of a printing-press or 20 transferred to other mechanism for further manipulation of the sheets. The bank or body of sheets passes from the supply-table to the feed-table through a curved throat, which reverses the position of the bank, so that the 25 bottom of the bank upon the supply-table becomes the top of the bank upon the feed-table. The top sheet upon the feed-table is acted upon by combing-rolls, which separate 30 said sheet from the bank and advance it between revolving rolls, which deliver said sheet to the registering devices. With this 35 class of machines the mechanism for separating the sheets from the bank is located under the supply-table and near the curved throat through which the sheets pass, and it has been customary to pivot the supply-table at its front end, so that said table can be 40 swung up when access is desired to the separating mechanism or other parts below the supply-table. When the supply-table is thus 45 swung up, there is nothing to retain the sheets upon the table, and it is therefore necessary to remove the sheets which have not their ends so far advanced through the curved throat that they will not be withdrawn by 50 their own weight when the table is swung up. When the feathered bank of sheets has been thus separated in the curved throat, it is impossible to replace the removed portion of the bank in the correct relation with the portion remaining, and it is therefore necessary

to exhaust that portion of the bank remaining upon the lower feed-table and in the throat and then thread a new bank of feathered sheets through the throat.

55

It is accordingly one object of the present invention to provide a construction in which access may be had to the separating and other devices under the supply-table without disturbing that portion of the bank of sheets which 60 is in the curved throat between the supply and feed tables, and this is accomplished by forming the supply-table in sections which are pivoted together. When access is desired to the mechanism beneath the supply-table, the bank on the supply-table may be 65 folded upon itself and be supported by the forward section, while the rear section is swung up.

With the above class of machines it is sometimes found after threading up the machine or after running for some time that the sheets are not being delivered in the proper relation to the side registering devices—that is to say, the sheets may be delivered too far from the 70 side guides and will not therefore be brought against the guides by the devices for moving the sheets laterally, or they may be delivered too near the side guides and will then be 75 crippled against the side guides by the laterally-moving devices, and in either case the sheets will not be delivered to the printing-press or other machine in proper register. Heretofore when this has occurred it has been 80 customary to stop the machine and to work 85 the bank of sheets upon the tables laterally in relation to the feeding and separating devices, and this was repeated whenever the sheets were being fed out of proper relation with the registering devices.

90

A further object of the invention is to provide means for conveniently and quickly adjusting the position of the bank of sheets with relation to the side register devices, and this is accomplished by making the feeding-table 95 in sections and rendering the rear section, which supports the supply-table and the separating mechanism, laterally adjustable.

In the accompanying drawings, Figure 1 shows a longitudinal section of so much of a 100 feeding-machine as is necessary to illustrate the application of the present improvements

thereto. Fig. 2 is a partial plan view of the lower feed-table with the supports for the separating mechanism and the upper supply-table removed, and Fig. 3 is a detail of 5 the connection between the sections of the upper supply-table.

Referring to the drawings, 1 represents the cylinder of a printing-press provided with the usual front guides 2. The feed board or table 10 3 is arranged with its delivery end over the cylinder and in position to be engaged by the front guides 2. Near the delivery end of the feed-table are the side register devices 4^a, which may be of any usual construction—as 15 for instance, of the construction shown in Patent No. 562,797, granted June 30, 1896. The sheets are delivered to the side register devices and the front guides by the delivery-rolls 4 and 5, located on opposite sides of the 20 path of the sheets. The feathered bank of sheets rests upon the feed-table in the rear of the rolls 4 and 5, and the sheets are separated from the bank and fed successively to these rolls by the action of combing-rolls 6, which 25 may be operated in any suitable and well-known manner. The bank of feathered or combed-out sheets is delivered upon the feed-table from an upper supply-table, which is arranged above the feed-table with its front 30 end over the rear end of the feed-table. The bank of sheets passes from the supply to the feed table through a curved throat formed between the feed-wheels 7, located at the end of the supply-table, and the curved guides 8, 35 secured to the rear end of the feed-table. Pressure-rolls 9 are located above the feed-wheels and act to press the sheets against the feed-wheels and insure a positive feeding of the bank of sheets. The bank upon the 40 supply-table rests upon endless bands 9^a, which extend along the upper face of the table, around the feed-wheels, and back over guide 10 and roll 11. The feed-wheels and pressure-rolls may be operated in any well-known 45 manner to advance the bank of sheets through the curved throat and to the separating devices.

The supply-table is formed in two sections 12 and 13, the front section of which is pivoted to standards 14 at 15 and is supported at each side by a brace 16, pivoted at 17 to the rear end of rib 16^a, secured to the under side of the section. The brace 16 is also pivoted to a link 18, which is in turn pivoted to the standards 14. The lower end of the brace 16 rests upon a stop 19 on the link 18. The rear section 12 of the supply-table is provided at each side with a supporting-bracket 13^a, pivoted at 17 below the surface of the front 55 section. Each bracket 13^a is provided with depending arms 20, which engage the braces 16, and thus support this section, while allowing it to be readily swung up into the dotted-line position, Fig. 1. When it is desired to 60 gain access to the parts under the supply-table without disturbing the bank of sheets in the curved throat, that part of the bank which

is upon the rear section is folded over onto the front section and the rear section is swung into the dotted-line position, where it is supported in a vertical position by the engagement of its front edge with the top of the front section. In setting up the machine for a new class of work, at which time there is no bank of sheets upon the tables and through 70 the curved throat, the upper table may be swung up about the pivot 15, the rear section being first swung up about its pivot, so that the table may be more conveniently handled and will occupy less space. 75

The upper supply-table, the feeding devices for transferring the bank of sheets to the lower feed-table, and the devices for separating the individual sheets from the bank are all supported by the standards 14, mounted upon the 80 rear portion or section of the lower feed-table. This section 21 of the feed-table, which also supports the front end of the banks of sheets, is so mounted that it may be adjusted laterally with relation to the front portion or 85 section of the feed-table which carries the registering devices. As shown, the rear section 21 rests upon transverse bars 22, secured between the side rails 23, and said section is guided by bars 24, secured to its under surface and engaging the sides of bars 22. A nut 25 is secured to the under surface of the section 21 and is engaged by a screw-rod 26, journaled in the side rail 23 and provided with a squared outer end for receiving a 90 wrench or operating-handle. By turning the rod 26 the bank of sheets and the devices acting thereon may be adjusted laterally while the machine is running and the sheets 95 presented to the delivery-rolls and register 100 devices in the proper manner.

The front portion of the feed-table may be hinged, as at 27, to plates 28, secured to the side rails 23, as indicated by dotted lines in Fig. 1. The front part of section 21 is cut 110 away, as at 29, Fig. 2, to allow the lateral adjustment of said section.

What I claim as my invention, and desire to secure by Letters Patent, is—

1. The combination of a supply-table comprising a front section and a rear section pivoted thereto, a feed-table below said supply-table, a curved throat leading from the front of the supply-table to the rear of the feed-table, and mechanism for feeding a bank 115 of feathered sheets from said supply-table through said throat, substantially as described.

2. The combination of a supply-table, comprising a front section and a rear section pivoted thereto, a feed-table below said supply-table, a curved throat leading from the front of the supply-table to the rear of the feed-table, mechanism for feeding a bank of feathered sheets from said supply-table to said 125 feed-table, and mechanism for separating the sheets from the bank on the feed-table, substantially as described.

3. The combination with mechanism for

feeding and reversing a bank of feathered sheets, of a supply-table having a front section pivoted adjacent said means, and a rear section pivoted to said front section, substantially as described.

4. The combination with mechanism for feeding and reversing a bank of feathered sheets, of a supply-table, having a front section, and a rear section pivoted to said front section below the surface thereof, substantially as described.

5. The combination of a feed-table having a front section and a laterally-adjustable rear section registering devices carried by the front section, and mechanism carried by the rear section for separating sheets from a pile of feathered sheets, substantially as described.

6. The combination of a feed-table, having a front section and a laterally-adjustable rear section, registering devices on the front section, a supply-table supported by said rear section, and mechanism supported by said rear section for feeding a bank of feathered sheets from said supply to said feed table, and

mechanism for separating individual sheets 25 from the bank on the rear section of the feed-table, substantially as described.

7. The combination of a feed-table having a front and a rear section, registering devices on said front section, mechanism on the rear 30 section for feeding a bank of feathered sheets and separating individual sheets therefrom, and means for adjusting the rear section laterally, substantially as described.

8. The combination of a feed-table having 35 a front section and a rear section, a supply-table supported by the rear section, a curved throat leading from the front of the supply-table to the rear of said rear section, feeding-wheels forming one side of said throat, combining-wheels supported by said rear section, and 40 means for adjusting the rear section laterally, substantially as described.
